UNITED STATES PATENT OFFICE.

ROBERT C. RUSSELL, JOHN A. WHITE, AND R. B. HAYDEN, OF DALLAS, TEXAS,
ASSIGNORS TO CARL R. JACKSON, OF DALLAS, TEXAS.

VENDING MACHINE.

Application filed June 1, 1926. Serial No. 112,861.

This invention relates to new and useful improvements in vending machines.

The object of the invention is to provide a vending machine for cylindrical articles such as pencils, which will be positive and reliable in operation and of simple construction involving a comparatively few number of parts.

A particular object of the invention is to provide a coin controlled actuating means arranged to positively prevent the operation of the vending carrier except when a certain coin or check of the proper diameter is inserted in the machine and to prevent operation when other coins or checks are used.

Another object of the invention is to provide a spring latch for holding the carrier against operation together with an actuator employing the coin as a means of lifting the latch to permit operation of the carrier.

A further object of the invention is to provide a carrier co-acting with a discharge hopper and equipped with means for agitating, selecting and positioning the article to be vended, in a new and novel manner.

A construction designed to carry out the invention will be hereinafter described, together with other features of the invention.

The invention will be more readily understood from a reading of the following specification and by reference to the accompanying drawings, in which an example of the invention is shown and wherein:

Fig. 1 is a front elevation of a machine constructed in accordance with the invention,

Fig. 2 is a side elevation of the same,

Fig. 3 is a vertical sectional view taken on the line 3-3 of Fig. 1,

Fig. 4 is a face view of the actuator,

Fig. 5 is a longitudinal vertical sectional view taken on the line 5-5 of Fig. 6,

Fig. 6 is a horizontal cross-sectional view taken on the line 6-6 of Fig. 5,

Fig. 7 is a transverse vertical sectional view taken on the line 7-7 of Fig. 1,

Fig. 8 is a transverse vertical sectional view taken on the line 8-8 of Fig. 6,

Fig. 9 is a detail showing one of the carrier guideways, and

Fig. 10 is a vertical sectional view on the line 10-10 of Fig. 3.

In the drawings the numeral 10 designates a suitably shaped housing or case having a window 11 in its upper portion, a removable

back plate 12 secured by a suitable lock 13, 55 a base 14 and a front opening 15 immediately over the base. The base has a flange 16 which extends across the opening 15, which acts to prevent the pencils from rolling forwardly off of the base. An inclined 60 deflector plate 17 bent upon itself is fastened on the base within the housing to guide the pencils toward the opening 15 as they fall from the compartment at the upper end of the casing.

Within the casing a pair of upright transverse frame plates 18 are secured and extend from the base to the top of the casing. These plates are spaced from the end walls of said casing and the opening 15 is confined therebetween. Each plate is bent just below its central portion to form horizontal transverse guideways 19 which are inclined forwardly as is best shown in Figs. 7, 8 and

9. A vending carrier 20, which may be in the form of a flat plate, has its ends slideable in the guideway 19, while adjacent its ends lugs 21 are cut from the plate and bent downwardly or provided in any other way.

These lugs are formed in pairs so as to engage on each side of the crank 22 of a crank shaft 23 journaled in the plates 18. The crank shaft extends through one of the end plates 24 of the casing 10 and has a crank handle 25 fastened thereon whereby said shaft may be rocked to cause its crank to slide the carrier.

A longitudinal hopper plate 26 has its ends fastened to the plates 18 and extends over the carrier. This plate has a bottom lip 27 overlying the carrier. The plate 26 is positioned at the rear of the casing and a front hopper plate 28, secured between the plates 18, has its lower edge overhanging the forward edge of the lip 27 (Figs. 7 and 8), and is spaced above the same to form a longitudinal discharge opening 29. The lip 27 is inclined forwardly and the opening 29 is just high enough to permit one pencil to roll therethrough.

A compartment is formed above the hopper plates 26 and 28 opposite the window 11 and this compartment contains the pencils or other cylindrical objects which are to be vended. In order that the pencils may be kept in parallel order or readily dispensed, upright fingers 30 and 31 are provided on a carrier and extend upwardly

through slots 32 and 33 in the plates 26 and 28 respectively. There are two pairs of these fingers spaced apart and each pair comprising a rear finger 30 and a front finger 31 spaced therefrom, the finger 30 being slightly higher than the finger 31 and the upper edges of the fingers being rounded. The carrier is provided with a longitudinal slot 34 located between the fingers 30 and 31 and of sufficient length to permit one pencil to fall therethrough. This slot normally underlies the lip 27 as is shown in Fig. 7.

It will be seen by observing Figs. 7 and 8 that upon rocking the crank 22 in a counter clockwise direction the carrier 20 will be slid forwardly. The lowermost pencil resting upon the lip 27 and between the fingers 30 and 31 will be carried thereby through the opening 29 while the remaining lower pencils will ride on the rounded edges of the fingers as the latter slide through the slots 32 and 33. After the pencil is carried through the opening 29 it will roll off the forward edge of the lip 27 and fall through the slot 34. The falling pencil striking upon the deflector 17 will be guided to the opening 15. When the crank 22 is swung in a clockwise direction the carrier 20 will be slid back to its normal position and the fingers will agitate the pencils so that one of said pencils will roll down between the fingers and rest upon the lip 27.

One of the frame plates 18 is spaced from the end plate 24 and the shaft 23 extends across this space. An actuator 35 in the form of a disk is mounted on said shaft adjacent the end plate 24 and has a hub 36 integral therewith and fastened on said shaft by a set screw 36'. The hub extends to the plate 18. A coiled spring 37 has its upper end fastened on a stud 38 on the housing, while its lower end is attached to a link 39 fastened to the hub by a screw 40 (Fig. 3). When the shaft 23 is rotated by the handle 25, the link 29, which is flexible, is rotated with the hub 36, thus placing the spring 37 under tension. When the handle is released the spring will return the parts to their normal positions.

On the inner face of the plate 24 a boss 41 is formed and this boss is provided in its face with an angular coin chute 42, the portions of which are sufficiently offset to overhang each other and cause a coin in passing through said chute to take a circuitous path. This also prevents the insertion of a wire and fraudulently operating the device. A cover plate 43 (Fig. 3) is fastened to the face of the boss over the chute. This plate terminates just over the actuator 35 which latter is contiguous to the lower end of said boss.

The actuator has a latch shoulder 44 provided on its periphery and is also provided

with an upper stop 45 and a lower stop 46. A pin 47 alternately engaged by these stops, limits the rotation of the actuator. A latch 48 pivoted on a stud 49 secured to the inner side of the end wall 24 has a right-angular head 50 (Fig. 10) directed toward the plate 24 and resting on a boss 51. The head has a depending dog 52 which overhangs the periphery of the actuator between the upper stop 45 and the shoulder 44 and in the path of the latter. A harp spring 53 hinged about the stud 49 has one end engaging over the latch, whereby said latch is resiliently held in position.

As is best shown in Fig. 4, the actuator 35 has its face next to the plate 24 cut out and provided with inclined guides 54 and 55 respectively located on opposite sides of the shaft 23 and extending downwardly from a supporting boss 56, which latter is normally directly under the chute at the lower end of the boss 41. Opposite the guide 54 the actuator has a lip 57. This lip is spaced at such a distance from the guide 54 as to prevent the passage of a nickel therebetween, but to allow a dime or a penny to roll from the boss 56 down said guideway. The distance from the boss 56 to the shoulder 44 is such that a nickel supported on said boss will project beyond the shoulder so that when the actuator is rotated in a clockwise direction (Fig. 3), the projecting edge of the nickel will ride under the dog 52 and elevate the latch so as to permit the shoulder to pass whereby the crank 22 may be rocked to operate the carrier. The operation of the actuator is limited by the engagement of the stop 45 with the pin 47. The guide 55 provides clearance for the nickel to roll out over the pin 47 and drop into the bottom of the housing after the latch has been actuated.

The operation of the machine having been clearly explained, it is not believed necessary to recite the various steps. It will be evident that upon dropping the proper coin into the chute 42, which has its entrance at the front of the casing, said coin or check will lodge upon the boss 56. The operator merely has to pull the handle 25 forwardly whereby the coin will engage the dog 52 and raise the latch 48, thus permitting the shaft 23 to rock its crank 22, which will slide the carrier 20 forwardly and carry the lowermost pencil through the opening 29 from which it will drop through the slot 34 to the base 14 of the case. The pencil may be removed through the opening 15. It will be seen that the machine can not be operated without inserting a coin, because if the handle 25 is pulled forward the shoulder 44 will engage the dog 52 and prevent further rotation of the actuator 35, and said handle can not be swung rearwardly because of the engagement of the stop 46 with the pin 47.

Various changes in the size and shape of

the different parts, as well as modifications and alterations, may be made within the scope of the appended claims.

What we claim, is:

- 5 1. In a vending machine, a casing, upright frame members in the casing having guideways, a carrier slidable in said guideways, a compartment, a hopper at the bottom of said compartment, upright fingers on said carrier 10 slidable transversely through the hopper, said carrier having a slot between its fingers normally closed by the bottom of the hopper, a crank shaft journaled in the casing and having a rocking connection with the carrier, 15 means exterior of the casing for rocking the shaft, and means in the casing for returning the shaft.

2. In a vending machine, a casing, upright frame members in the casing having inclined guideways, a carrier slideable downwardly in said guideways, a compartment, a hopper at the bottom of said compartment, upright fingers on said carrier slideable transversely through the hopper, said carrier having a slot between its fingers normally under the bottom of the hopper, a crank shaft journaled in the casing, and a connection depending from the carrier and engaging the shaft. 20 25

In testimony whereof we affix our signatures. 30
